UNITED STATES PATENT OFFICE

104,966

DESIGN FOR AN ELECTRIC CHIME

Evan G. Evans, Cincinnati, Ohio, assignor to
Nutone Chimes, Inc., New York, N. Y., a cor-
poration of New York

Application April 20, 1937, Serial No. 68,893

Term of patent 3½ years

To all whom it may concern:

Be it known that I, Evan G. Evans, a citizen of the United States, residing at Cincinnati, in the county of Hamilton and State of Ohio, have invented a new, original, and ornamental Design for an Electric Chime, of which the following is a specification, reference being had to the accompanying drawing, forming a part thereof.

The figure is a perspective view of the electric chime showing my new design.

I claim:

The ornamental design for an electric chime as shown.

EVAN G. EVANS.
